UNITED STATES PATENT OFFICE.

ROBERT DEY, OF SYRACUSE, NEW YORK.

DESIGN FOR A HANDKERCHIEF-BOX.

No. 37,602.

Specification for Design.

Patented Oct. 31, 1905.

Application filed September 12, 1905. Serial No. 278,196. Term of patent 3½ years.

To all whom it may concern:

Be it known that I, ROBERT DEY, a citizen of the United States, residing in the city of Syracuse, county of Onondaga, and State of New York, have invented a new, original, and ornamental Design for a Handkerchief-Box, of which the following is a specification, reference being had to the accompanying drawing, in which I show the handkerchief-box in isometric perspective.

What I claim is—

The ornamental design for a handkerchief-box, as shown.

ROBERT DEY.
